US0D1046837S

(12) **United States Design Patent** (10) **Patent No.:** **US D1,046,837 S**
(45) **Date of Patent:** **** Oct. 15, 2024**

(54) **TELEVISION RECEIVER**

- (71) Applicant: **Samsung Electronics Co., Ltd.**, Suwon-si (KR)
- (72) Inventor: **Kyoosang Choi**, Suwon-si (KR)
- (73) Assignee: **SAMSUNG ELECTRONICS CO., LTD.**, Gyeonggi-Do (KR)
- (**) Term: **15 Years**
- (21) Appl. No.: **29/844,118**
- (22) Filed: **Jun. 27, 2022**

(30) **Foreign Application Priority Data**

- Dec. 28, 2021 (KR) 30-2021-0062738
- (51) **LOC (14) Cl.** **14-06**
- (52) **U.S. Cl.**
USPC **D14/239**
- (58) **Field of Classification Search**
USPC D14/336, 348-349, 353-358, 371-382,
D14/389, 440, 432-435, 454, 447-452,

(57) **CLAIM**

The ornamental design for a television receiver, as shown and described.

DESCRIPTION

FIG. 1 is a front perspective view of a television receiver, showing my new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a rear perspective view thereof;
FIG. 9 is an enlarged view of the portion 9 in FIG. 2;
FIG. 10 is an enlarged view of the portion 10 in FIG. 5; and,
FIG. 11 is an enlarged view of the portion 11 in FIG. 8.
The even-dash broken lines illustrating portions of the television receiver form no part of the claimed design. The dot-dot-dash broken lines encircling enlargement portions of the claimed design form no part of the claimed design.

1 Claim, 10 Drawing Sheets
